HENRY S. HITNER, OF MARBLE HALL, PENNSYLVANIA.

Letters Patent No. 86,014, dated January 19, 1869.

IMPROVEMENT IN HORSE-SHOES.

The Schedule referred to in these Letters Patent and making part of the same.

To all whom it may concern:

Be it known that I, HENRY S. HITNER, of Marble Hall, in the county of Montgomery, and State of Pennsylvania, have invented a new and useful Improvement in Horse-Shoes; and I do hereby declare the following to be a full, clear, and exact description of the same, sufficient to enable others skilled in the art to which the invention appertains, to fully understand and use it, reference being had to the accompanying drawings, forming part of this specification, and in which—

Figures 1 and 2 are sections through line $x x$ of fig. 3.

Figure 3 is a perspective view.

This invention relates to that class of horse-shoes in which a plain curved plate, without calks, is fastened to the hoof, and to this plate the shoe, bearing either sharp or dull calks, is attached by means of screws.

This improvement relates to a new device for strengthening the shoe, and attaching it to the curved plate more firmly than has been done heretofore.

In the drawings, A is the curved plate, of the general form of a horse-shoe without calks, and provided with the holes $a a$, through which it is nailed to the animal's hoof, and two or more screw-holes, $c c$, through which the screws pass that fasten the shoe to the plate.

It may also be provided with a counter-sink, at d , to receive the lip or flange, hereinafter described.

B is the shoe, provided with sharp calks, as seen in fig. 1, or dull ones, as shown in fig. 2, for use in winter or summer, respectively, and capable of being firmly and securely fastened to the plate A, by means of screws $e e$, and a bent-up lip, flange, or hook, D, which slips upon the plate A at the counter-sink, as shown in figs. 1 and 2.

The improvement which I desire to secure, consists essentially in the employment of the bent-up lip D, which clamps the shoe and the plate firmly together at their front end, and saves the necessity for screws at that point. The tip being a part of the shoe, is

naturally driven more firmly upon the plate by the action of the horse's feet, there being very little tendency, under any circumstances, to force the shoe back off the plate. The screws $e e$ are therefore relieved of much of the strain to which they would otherwise be subjected.

The whole forms a neat, light, and durable horse-shoe, which can be easily and readily changed, so as to have sharp or dull calks, at pleasure, by removing the lower plate, and substituting for it another, such as may be needed.

I am aware that it is not new to attach a false shoe, provided with calks, to the ordinary shoe, by means of clips; neither is it new to attach such shoe by means of screws alone; but both of these ways are objectionable—the former, in that the shoe which is jointed at the toe requires a screw, not only to spread the false shoe apart at the heel, so that the clips will take hold upon the shoe nailed to the animal's hoof, but also to cause the clips to retain such hold upon the shoe; and the latter in that all the strain being upon the screws, they are continually working loose, and thus liable to break off. I therefore wish it distinctly understood that I lay no claim to either of the above-described modes of fastening; but having fully described my invention,

What I do claim, and desire to secure by Letters Patent, is—

The horse-shoe herein-described, consisting of the two parts, A and B, when the same are made each of a solid piece of metal, and fastened together at the heel by the screws $e e$, and at the toe by the bent clip or flange D, fitting a counter-sink in the upper surface of the part A, substantially in the manner and for the purpose set forth.

HENRY S. HITNER.
